UNITED STATES PATENT OFFICE

JAMES B. TRIPPLETT, DECEASED, LATE OF WHITTIER, CALIFORNIA, BY WILLIAM H. CAMPBELL, OF LOS ANGELES, CALIFORNIA, AND WILLIAM H. MAXWELL, OF BEVERLY HILLS, CALIFORNIA, CO-EXECUTORS, ASSIGNEES TO JOHN GRANT, OF LOS ANGELES, CALIFORNIA

WELL REAMER

Application filed December 5, 1928. Serial No. 323,907.

This invention has to do with a well reamer and relates particularly to an expansion reamer useful in the drilling of wells with the rotary method. The tool is intended to be used when it is desired to underream or enlarge a well bore or to straighten a well bore.

It is a general object of the present invention to provide an improved, practical arrangement and formation of parts in a tool of the character mentioned. The invention provides a reamer in which the parts are related and proportioned so that they are effective and practical for actual drilling operations.

15 It is another object of the invention to provide various improvements in the cutters or cutting means of a tool of the character mentioned whereby the tool is made effective, dependable, and commercially practical.

20 Another object of the invention is to provide an improved type of cutting means and an improved mounting of such cutting means in a tool of the character mentioned. By the present invention the cutting means or cutter units are effectively and dependably secured in the tool.

25 There are numerous other objects and features of the present invention which will be understood from the following detailed description of a typical form and application of the invention, throughout which description reference is had to the accompanying drawings, in which:

30 Fig. 1 is a longitudinal detailed sectional view of the upper portion of the tool showing the parts in collapsed or retracted position.

35 Fig. 2 is a longitudinal detailed sectional view of the lower portion of the tool showing the parts in position corresponding to that in Fig. 1.

40 Fig. 3 is a view similar to Fig. 1 showing the parts expanded or in operating position.

45 Fig. 4 is a view similar to Fig. 2 showing the parts in position corresponding to that shown in Fig. 3.

50 Fig. 5 is an enlarged sectional view of a portion of the parts shown in Fig. 4 being a view showing in detail the manner in which the upper end portion of a cutter unit is

secured in the main parts of the tool when the tool is in operating position.

55 Fig. 6 is an enlarged detailed transverse sectional view taken as indicated by line 6—6 on Fig. 4.

Fig. 7 is an enlarged detailed transverse sectional view taken as indicated by line 7—7 on Fig. 4.

60 Fig. 8 is an enlarged transverse sectional view taken as indicated by line 8—8 on Fig. 4.

65 The tool provided by this invention includes, generally, two main sections A and B, a plurality of cutters or cutter units C carried by the main sections to be operable by relative movement between the sections, means D for causing relative movement between the sections, and a control E for the means D.

70 The main parts or sections of the tool may be formed and related in various manners, it being important, generally, that they be such as to effectively support or carry the cutter units, that they be relatively movable to effect operation of the cutter units, and that they accommodate the means D and the control E. Certain of the important features of the present invention are in no way concerned with the various details of design or formation of the parts A and B, and therefore the following detailed description of 75 these parts is to be considered principally for the purpose of facilitating a full understanding of the invention and not as limiting or restricting the invention as defined in the claims.

80 The main section A is the central or inner section of the tool, while the section B is the outer section. In the particular arrangement illustrated the section A is adapted to be attached to the lower end of a string of 85 drill pipe or other operating means and may therefore be considered the upper section while the section B is carried by the inner section and extends downwardly below the inner section and therefore may be considered the lower section of the tool.

90 The inner section A of the tool includes an elongate body 10 and a wedge head 11 on the body. In the arrangement shown the body is provided at its upper end with means for 95 100

attachment with a string of drill pipe, or the like, while the head 11 is provided on the lower end of the body. In the drawings the upper end of the body 10 is shown provided with threads 12 to carry a sub 13 for making connection with the drill pipe. The tool, being designed for use with the rotary method of drilling, is provided with a central longitudinal circulation opening 14 formed through the section A, and, in accordance with the invention, the circulation opening has a portion 15 of reduced diameter at the lower end of the section, that is at the head portion of the section.

15. The outer section B of the tool includes, generally, a body 16 carried on the lower end portion of the section A, a tubular extension 17 extending upwardly from the body 16 around the section A, and a head 18 on the upper end of the tubular extension 17.

The body portion 16 of the section B has an upper end portion carried on the lower part of the inner section A, has a middle portion having openings carrying the cutter units, and has a lower portion which may be used to carry a pilot bit 19 and pilot cutters 20, as desired. In accordance with the preferred form of the invention, the upper end portion of the body 16 fits over the head 11 and lower end portion of the body 10 of the section A, while the middle portion of the body 16, continues downwardly to a point below the head 11 of the section A. The middle portion of the body 16 has vertical or longitudinally disposed openings for the reception of the cutter units. In the particular formation illustrated, the middle portion of the body 16 is tubular and the openings 21 are in the form of slots in the tubular wall. The lower end portion of the body 16 is preferably provided with a pilot bit 19. In the case illustrated the pilot bit 19 is detachable from the body 16, the body being provided with a screw threaded socket 22 to receive a pin 23 on the shank of the pilot bit.

50. Pilot reaming cutters 20 carried by the lower end portion of the body 16 may be in the form of roller cutters carried in sockets 24 provided in the body, as shown in Figs. 2 and 4 of the drawings. In the preferred arrangement the mounting pins 25 extend into the lower end portion of the body 16 from its lower end to project upwardly through the sockets 24. The pins 25 are held in place by the shank of the bit 19 which engages the lower end of the body 16, as clearly shown in the drawings.

55. In accordance with the present invention the main sections A and B are related or connected for limited relative movement vertically or longitudinally of the tool and are related or connected against relative rotation. The sections A and B are connected against relative rotation at or adjacent the head 11 of the section A through cooperating

longitudinally disposed ribs and recesses. In the preferred form of the invention a plurality of longitudinally disposed ribs 26 project outwardly from the body 10 of the section A adjacent the head 11 and are disposed longitudinally on the body. The upper end portion of the body 16 of section B is provided with an opening 27 slidably carrying the lower end portion of the body 10 of section A, and the walls of the opening 27 are provided with longitudinally disposed recesses 28 slidably carrying the ribs 26 on the section A.

60. The tubular extension 17 of section B extends upwardly from the body 16 around the section A fitting the section A with substantial clearance to form a chamber 30. The head 18 is attached to the upper end of the extension 17 and has an opening 31 slidably carrying the body 10 of the section A. In accordance with the preferred construction the extension 17 is screw threaded on the upper end of the body 16 while the head 18 screw threads into the upper end of the extension.

65. The means D provided for causing relative longitudinal movement between the sections A and B is preferably a spring means and in the particular case illustrated comprises a helical spring 32 arranged in the chamber 30 between an upwardly facing shoulder 33 on the body 10 of section A and a downwardly facing shoulder 34 on the head 18 of section B. The spring 32 is a compression spring proportioned so that the section B is normally yieldingly urged upwardly on or relative to the section A.

70. The control E provided for controlling movement between the sections through the action of the means D is provided for the purpose of putting the tool under control of the operator so that it can be tripped or released for operation whenever desired. The control is preferably a hydraulic control means actuated by the circulating fluid. In the drawings the control E is shown as including a hydraulic trip which includes a latch 36 for releasably holding the sections A and B of the body apart, or positioned as shown in Fig. 1, and a hydraulic trigger 37 for controlling the latch. The latch 36 is shown mounted in an opening 38 provided in the body 10 of section A. The latch 36 has a head with a beveled face 39 designed to cooperatively engage a beveled face 40 on the head 18 of section B.

75. When the latch is out or in position to hold the sections A and B in the positions shown in Fig. 1, the faces 39 and 40 are in cooperative engagement and act to tend to move the latch 36 inwardly or to the released position. Such inward movement of the latch 36 is resisted by the hydraulic trigger 37 which is pivotally mounted in the circulation opening 14 of the body 10. The trigger 37 is pivotally

carried by a sleeve 41 mounted in the opening 14. The trigger when up, or in position to hold the latch 36 out, closes the opening through the sleeve 41, as shown in Fig. 1. 5 When circulation fluid is forced downwardly into the tool, for instance from the string of drill pipe to which the tool is connected, the trigger 37 is forced downwardly allowing the latch 36 to move inwardly so that the section B is released and allowed to move upwardly on the section A.

The present invention provides one or more cutter units C, it being preferred in most cases to use three cutter units equally spaced 15 around the central axis of the tool. The cutter units are mounted in or carried by the sections A and B so that they are shiftable from a collapsed or retracted position, such as is shown in Fig. 2, to an operating or expanded position such as is shown in Fig. 4. This operation or expansion of the cutter units is caused by relative movement between the wedge head 11 of the section A and the cutter units. In the case illustrated the cutter 25 units are bodily carried by the section B of the tool so that the relative movement of the section B with reference to the section A causes the desired relative movement between the cutter units and the wedge head 11 of 30 the section A. The wedge head 11 has a plurality of upwardly and outwardly extending wedge faces 43 to cooperatively engage the cutter units.

In accordance with the present invention 35 the number and arrangement of ribs 26 on the section A corresponds to that of the wedge faces 43 so that the wedge faces extending upwardly and outwardly on the head 11 join or extend onto the ribs 26. With this construction or arrangement, the upper end portion of the body 16 of section B has sliding bearing engagement with the section A between the wedge faces 43 thus establishing an effective direct driving engagement between 40 the sections at the cutter supporting portions of the sections.

In practice the several cutter units C of a single tool are preferably alike and therefore a detailed description of one unit will be 45 given, it being understood that such description may apply to all of the units.

The cutter unit C includes, generally, a plurality of revolving cutters, a pin for carrying the cutters, and upper and lower mounting blocks 44 and 45, respectively, carrying the pin.

In the preferred form of the invention there is a plurality of upper roller cutters 46 carried on the upper end portion 47 of the pin and a plurality of lower cutters 48 carried on the lower portion 49 of the pin. The pin is bent intermediate the upper and lower portions 47 and 49, or, in other words, is formed so that the sections 47 and 49 are angularly disposed relative to each other, and the upper

section 47 is substantially larger in diameter than the lower section 49. In the preferred relationing of parts the upper section 47 of the pin is substantially parallel with the longitudinal axis of the tool when the cutter unit is in operating position as shown in Fig. 4, while the lower section 49 extends upwardly and outwardly, its upper end joining or being integral with the lower end of the upper section 47, as shown in the drawings. 70

The cutters 46 on the upper end portion 47 of the pin are roller cutters having toothed outer faces extending substantially parallel to the portion 47 of the pin so that they are parallel with the longitudinal axis of the tool when in operation. The cutters 46 on the lower portion 49 of the pin are provided with toothed outer faces which are tapered or conically shaped so that they are substantially parallel with the longitudinal axis of the tool when in operation even though their axis of rotation is angularly disposed with reference to the longitudinal axis of the tool. 80

The mounting pin carrying the cutters 46 and 48 is carried by the sections A and B through the blocks 44 and 45. The block 45 carries the lower end of the pin and is attached to the outer section B of the tool, while the block 44 carries the upper end of the pin and has connection with the inner section A of the tool. The block 45 is mounted in the opening 21 in the body 16 of section B. In accordance with the invention, the block is retained in the opening 21 by a pivot pin 50 extending between opposite sides of the opening 21 and through the lower end portion of the block 45. The block 45 has an upward extension 51 extending upwardly behind or inward of the cutter carrying pin. The upper inner portion of the extension 51 is provided with a face 52 to bear on the wedge face 43 of the head 11 when the cutter unit is in operating position, as shown in Fig. 4. 90

In accordance with the present invention, flanges 53 and 54 project outwardly from the extension 51 to support the pin intermediate its ends. The flange 53 is arranged to support the upper end portion 47 of the pin and engages the portion 47 between adjacent cutters 46. The flange 53 has a notch 55 in its outer part in which the pin portion 47 seats. The flanges 54 engage the lower portion 49 of the pin and each flange engages the pin intermediate cutters 48. The flanges 54 preferably surround the portion 49 of the pin, that is they are preferably provided with bores 56 which slidably receive the portion 49 of the pin, as clearly shown throughout the drawings. 100

The extreme lower end of the pin portion 49 extends into a socket 57 provided in the lower portion of the block 45. The up thrust of certain of the cutters 46 and 48 is taken by the flanges of the block 45, while the up thrust of the uppermost cutters 46 is taken by a 110

shoulder 60 on a head provided on the upper end of the pin, and the up thrust of the uppermost cutters 48 is taken by the shoulder 61 occurring between the two pin portions 47 and 49.

6 The invention provides openings 62 through the extension 51 of the block 45 to allow circulating fluid admitted behind the extension 51 from the section A of the tool to discharge outwardly against the cutters of the unit. This keeps the cutters free and in operating condition.

10 The block 44 carries the upper end of the pin. The pin has a head 66 on the upper end of the portion 47 which head extends upwardly into an opening 67 formed vertically in the block 44. The block 44 is slidably supported on the wedge face 43 of the head 11. In the preferred construction the 15 block 44 is slidably keyed to the face 43 there being a dovetailed rib 70 on the block fitting a corresponding groove 71 in the face. The cutter unit is proportioned so that the block 44 is located adjacent the upper end 20 of the opening 21, and in the preferred form of the invention the block has an upwardly extending tongue projecting upwardly to extend into the body part 16 of section B above the opening 21 when the cutter is in operating 25 position, as shown in Fig. 4.

30 The head 66 of the pin has a tongue 73 which likewise projects upwardly into the body part 16 above the opening 21, as clearly shown in the drawings. The head 66 and block 44 are connected by means of a pin 80 so that they have sufficient play or relative movement to allow for shifting of the parts between the positions shown in Figs. 2 and 4 of the drawings. In the preferred formation 35 of parts the tongue 73 extends into the recess 28 in the body part 16 and bears against the bottom of the recess when the parts are in position, as shown in Fig. 4, and at the same time the lower end 81 of the block 45 seats 40 on or abuts the lower end of the opening 21. Thus when the unit is in operating position it is rigid or firm, being effectively held by both the sections A and B. It is to be particularly noted that the upper block 44 of the unit is supported by the section A as well 45 as the section B and that the cutter supporting pin of the unit is supported at its ends and at a plurality of points intermediate its ends.

50 The circulating fluid introduced into the opening 14 of the section A discharges into the body 16 of the section B behind the block extensions 51. A circulation opening 85 is formed through the lower portion of the body 16 to convey circulating fluid to the bit 19. In the form of the invention illustrated circulation openings 86 are provided in the head 11 of the section A between the opening 14 and the wedge faces 43 to direct circulating fluid onto the upper cutters 46 which are not

reached by circulating fluid discharged through openings 62.

5 In operating the tool it is applied to the lower end of a string of drill pipe, or the like, and before it is introduced into the well 7 the sections A and B are latched in the position shown in Figs. 1 and 2 so that the cutter units are in the contracted position. The tool is lowered into the well, for instance, through and to a point below the well casing, 71 and, when it has reached the point in the well where the reaming operation is to be performed, the control E is operated to release the spring 32 so that the body sections are moved relative to each other to cause expansion of the cutter units. Operation of the control E is accomplished by forcing circulation fluid downwardly to release the trigger 37 so that the latch 36 is released to allow relative movement between the sections 80 A and B to the positions shown in Figs. 3 and 4. Ordinarily the section A on the end of the string of drill pipe is stationary or is substantially stationary when the tool is tripped or released and therefore the spring 85 32 operates to move the main section B upwardly on the section A. This causes the cutter units to move upwardly relative to the wedge head 11 which obviously causes the upper ends of the cutter units to be wedged or forced outwardly to the position 90 shown in Fig. 4.

95 With the parts in the expanded position, the tool is ready for the reaming operation which operation is performed by rotating the tool and advancing it through the well bore. As the tool is rotated the lower cutters 48 operate to remove the material from the wall 100 of the bore, enlarging the bore until the upper cutters 44 operate to finally cut the bore to the desired size.

105 To withdraw the tool from the well, it is pulled upwardly. As the tool is moved upwardly any obstruction in the well or a shoe, or the like, on the lower end of a casing, engaging the blocks 44 of the cutter units, causes the blocks 44 to be moved downwardly relative to the section A, which causes them to be retracted or moved inwardly. In this manner the tool will automatically collapse 110 or become retracted in order to permit its withdrawal from the well.

115 From the foregoing description it will be apparent that the present invention provides a very simple, practical, compact arrangement of parts. Particular attention is directed to the arrangement, construction, and formation of parts in the cutter units. The cutter units are such that they can be very easily and quickly assembled and are such as to be secure and effective in operation when in place in the tool. The cutters or working parts of the cutter units are effectively supported and are effectively flushed with circu- 120

lating fluid so that they work freely and efficiently.

Having described only a typical preferred form and application of the invention, it is to be understood that the broader principles of the invention are not to be limited to details such as have been set forth, but that the invention is to be measured by the following claims.

10 Having described the invention, it is claimed:

1. A well reamer including, a cutter unit, and means carrying the cutter unit for tilting movement to expanded position, the unit including a cutter carrying pin, a cutter on the pin, and relatively movable blocks carrying the ends of the pin, one of the blocks having a part engaging the pin at a point intermediate its ends.

20 2. A well reamer including, a cutter unit, and means carrying the cutter unit for tilting movement to expanded position, the unit including a cutter carrying pin, a cutter on the pin, and relatively movable blocks carrying the ends of the pin, one of the blocks having a plurality of parts engaging the pin at spaced points intermediate its ends.

30 3. A well reamer including, a cutter unit, and means carrying the cutter unit for tilting movement to expanded position, the unit including a pin having angularly related cutter carrying parts, and separate blocks carrying the ends of the pin, one of the blocks having parts supporting said parts of the pin intermediate their ends.

40 4. A well reamer including, a cutter unit, and means carrying the cutter unit for tilting movement to expanded position, the unit including a pin having angularly related cutter carrying parts, cutters on the parts, and blocks carrying the ends of the pin, one of the blocks having parts supporting said parts of the pin intermediate their ends.

45 5. A well reamer including, a cutter unit, and means carrying the cutter unit for tilting movement to expanded position, the unit including a pin having angularly related cutter carrying parts, cutters on the said parts, and separate blocks carrying the ends of the pin, the block carrying the lower end of the pin having parts supporting said parts of the pin intermediate their ends.

55 6. A well reamer including, a cutter unit, and means carrying the cutter unit for tilting movement to expanded position, the unit including, a pin having angularly related cutter carrying parts, cutters on the said parts, separate parts supporting the ends of the pin, and means supporting said parts of the pin intermediate their ends.

60 7. A well reamer including, a cutter unit, and two sections carrying the unit for expansion, one section having an inclined part, the unit including a cutter carrying pin, a cutter on the pin and blocks carrying the ends of

the pin, both blocks having cooperative engagement with said part.

8. A well reamer including, a cutter unit, and two sections carrying the unit for expansion, one section having an inclined part, the unit including a cutter carrying pin, a cutter on the pin and blocks carrying the ends of the pin, both blocks having cooperative engagement with said part, and one block being pivotally connected with the other section.

70 9. A well reamer including, a cutter unit, and two sections carrying the unit for expansion, one section having an inclined part, the unit including a cutter carrying pin, a cutter on the pin, and blocks carrying the ends of the pin, both blocks having cooperative engagement with said part, one block having a circulation opening.

75 10. A well reamer including, a cutter unit, and two sections carrying the unit for expansion, one section having an inclined part, the unit including a cutter carrying pin, a cutter on the pin and blocks carrying the ends of the pin, both blocks having cooperative engagement with said part, and one block being pivotally connected with the other section and having parts supporting the pin intermediate its ends.

85 11. A well reamer including, a cutter unit, and two sections carrying the unit for expansion, one section having an inclined part, the unit including a cutter carrying pin, a cutter on the pin and blocks carrying the ends of the pin, both blocks having cooperative engagement with said part, and one block being pivotally connected with the other section and having parts supporting the pin at a plurality of spaced points intermediate its ends.

95 12. A well reamer including, a cutter unit, and means carrying the cutter unit for tilting movement to expanded position, the unit including, a pin having parts of different diameters forming a shoulder, and cutters rotatably carried on said parts, the cutters on one of said parts bearing against said shoulder.

105 13. In a well reaming tool two sections related for relative longitudinal movement one section extending into the other, a wedge head at the lower end of the inner section, longitudinal ribs on the said inner section slidable in recesses in the other section, the wedge head having inclined faces continuous with the ribs, and a cutter unit related to the wedge head for outward movement upon relative movement between the sections.

115 14. In a well reaming tool, two sections, an upper section and a lower section, the lower section extending over a portion of the upper section, the sections being related for relative longitudinal movement, a head at the lower end of the upper section, ribs on the upper section slidable in longitudinal recesses in the lower section, the head having inclined
